UNITED STATES PATENT OFFICE.

OSCAR A. SMITH, OF CLEVELAND, OHIO, ASSIGNOR TO THE NATIONAL-ACME MANUFACTURING COMPANY, OF CLEVELAND, OHIO, A CORPORATION OF OHIO.

NUT-TAPPING MACHINE.

1,056,065.

Specification of Letters Patent.

Patented Mar. 18, 1913.

Application filed April 21, 1911. Serial No. 622,485.

To all whom it may concern:

Be it known that I, OSCAR A. SMITH, a citizen of the United States, residing at Cleveland, in the county of Cuyahoga and State of Ohio, have invented certain new and useful Improvements in Nut-Tapping Machines, of which the following is a specification.

This invention relates to nut tapping machines, the object of the invention being to provide an improved machine of this character comparatively simple in construction and very rapid in its operation and effective in its work, and in which the tap will be supported and held by the nuts thereon after the tapping operation and before delivery from the discharge end of the tap, the machine in the present embodiment being constructed for use with the tap shown and described in my contemporaneously pending application Serial No. 603,811, filed January 21, 1911, for improvements in nut taps.

In the drawings accompanying and forming part of this specification, Figure 1 is a front view of this improved nut tapping machine; Fig. 2 is a side, partly sectional, view of the same; Fig. 3 is a top, partly sectional, view; Fig. 4 is a cross-sectional view of a part of the operating mechanism for the rotary table; Fig. 5 is a sectional view of part of such rotary table; Fig. 6 is a sectional view of such table showing it adapted for use with a different form of nut; Fig. 7 is an enlarged detail view of one of the nut receiving openings in the table shown in Fig. 6; Fig. 8 is a view of the nut holding plunger shown in Fig. 6; and Fig. 9 is a perspective view of the improved upright nut tapping machine.

Similar characters of reference indicate corresponding parts throughout the figures of the drawings.

The operating mechanism of this improved machine is carried by a suitable standard 2 having a supporting base 3, the standard being constructed at its upper end to form a housing 4 for parts of the operating mechanism. The tap 5 is mounted in a suitable tube or holder 6 carried by the enlarged tubular ends of a spindle 7 having a keyway 8 permitting the spindle to be reciprocated up and down.

Located in a projecting portion 9 of the housing, and keyed on this spindle is a pin-

ion 10 in mesh with a gear 11 carried by a shaft 12 suitably journaled in the top and bottom of the housing. On this shaft 12 is a bevel gear 13 in mesh with a bevel gear 14 carried by a horizontally located shaft 15 likewise suitably supported in the housing and the outer end of which is provided with a driving pulley 16 for the reception of a suitable belt. By this means the tap holder and the tap carried thereby are rotated at a very rapid speed, determined by the ratio of the gears 10 and 11 and the speed at which the driving pulley is rotated.

Located below the tap is a rotatable table or nut-blank receiving platen 17 having secured thereto a disk provided with a circular series of nut-blank openings 18, shown in Fig. 7 as of hexagonal shape, and in each of these openings a nut-blank is placed by the operator as the table is indexed or rotated. For rotating this table suitable ratchet mechanism is provided, this consisting of a ratchet wheel 19 secured adjacent to the lower end of the shaft or spindle 20 upon which the table is secured and which spindle is journaled in a suitable bracket 21 projecting forwardly of the standard 2. For rotating this ratchet wheel successively one tooth at a time a spring pressed pawl 22 is provided, this pawl being carried by an oscillatory arm 23 mounted on the spindle carrying the table. The opposite end of this arm is connected by a link 24 with a bell-crank lever 25 pivotally connected with the standard and operated by a cam 26 carried by a vertically located shaft 27 supported at its upper and lower ends by projecting brackets 28 and 29 from the standard, the shaft 27 being rotated by a bevel gear 27' carried thereon in mesh with a bevel gear 27'' secured on the end of a shaft hereinafter referred to. This cam 26 is provided with a set of cams or cam members 30 for operating the bell-crank lever and thereby rotating the table in the manner described, a suitable spring 32 being provided for returning the bell-crank lever to its normal position.

The underside of the table is provided with a toothed ring 33, coöoperating with which is a spring pressed bolt 34 carried by a bracket 35 on the standard, and this bolt is effective to lock the table at each indexing

thereof. The teeth of this toothed ring correspond in number with the number of blank receiving pockets in the rotatable table or nut blank carrier. Carried by an overhanging arm extending from the standard is a spring pressed plunger 40, pressing against a plunger 36 having a crotch or U-shaped portion 37 into which extends a roller 38 carried by a rock arm 39 supported on the standard, the opposite end of which rock arm is in position to be engaged by cams 31 on the shaft 27, whereby after each nut blank is tapped one of the cams 31 is carried into position to engage this rock arm and so shift the plunger 36 and release the same from the action of the spring actuated plunger 40 and so move it from its gripping or holding position as hereinafter explained.

When hexagonal or square nuts are to be tapped the table disk will be provided with openings of this form, which thus serve to hold the blanks against turning. When this form of blank holder is used the plunger 36 simply acts as an extra locating device, it having its end machined to enter stations or serrations formed on the edge of the table, there being as many stations as there are blank holding openings. When, however, a round nut blank is to be tapped a disk 43 having circular openings will be provided, and in this construction suitable toothed plungers 44 will be provided for holding each nut-blank in position, the plunger being located in the table so as to engage the side of the blank as shown in Fig. 6 and to project at the outer edge of the table. In this form of blank holder the end of the plunger 36 is left flat so that it will press against the end of each toothed plunger 44 as the table is indexed and so hold the round blank in position to be tapped. For adjusting the nuts depthwise relatively to the table an adjusting screw 42 is provided at the underside of the nut. This will also permit different depths of nuts to be positioned in the table.

For reciprocating the nut tap to carry it away from the finished blank and to bring it into engagement with the next blank to be tapped the tap holder spindle is provided with a spool or grooved collar 45, in engagement with which is a shoe 46 carried by a rock arm 47 pivotally supported on the standard, the opposite end of which arm is in position to be engaged by a cam 48 effective to rock the arm and thereby lift the tap holder and thereby the tap during the rotation thereof. This cam is fixed to a shaft 49 horizontally supported in the housing carrying the bevel gear 27' hereinbefore referred to, and this shaft 49 is rotated by a worm wheel 50 fixed thereto and in mesh with a worm 51 carried by a shaft 52 also mounted in the housing, and which 55 worm shaft receives motion through the

medium of a gear 53 mounted thereon and in mesh with an idler gear 54 to which motion is imparted by a gear 55 mounted on the shaft 12 between the gear 11 and the bevel gear 13. This idler gear is carried by a suitable shiftable arm so that when the gear 53 is changed the gears can be always perfectly meshed. A similarly supported shoe 70 to that hereinbefore described fits into the grooved collar of the tap holder spindle, this shoe being carried by a rock arm 71 suitably pivoted to the standard, the opposite end thereof carrying a counterbalancing weight 72 for the tap spindle and its holder. This weight is usually a little lighter than the spindle and acts as a balance weight.

From the foregoing it will be perceived that the weight of the tap spindle will normally carry the tap into position to engage a nut-blank during the rotation of the tap and that when such blank has been properly threaded the cam is rotated into position to engage the rock arm 47 and thereby lift the tap, which, on the passage of the cam surface from the rock arm, will immediately descend to permit it to engage another nut-blank which in the meantime has been carried into position under the tap.

The tap 5 as shown herein comprises a threaded end or head 61 having a straight portion or shank 62 terminating in a deflected portion 63 of large radial curvature which constitutes the crank by means of which, through the medium of the nuts, the tap is rotated, and this tap is mounted in the tubular holder hereinbefore described and having its inclosing part of the same formation as the tap, the holder being of larger diameter than the tap so as to provide proper room for the passage of the nuts along the shank of the tap, the holder being also of greater length than the tap. By rotating the holder in the manner hereinbefore set forth the tap is rotated through the medium of the nuts intermediate such tap and the holder in a manner which will be readily understood. In practice this tubular holder is slotted, as at 65, as is also the enlarged end of the spindle, thereby to permit ready access to the passing nuts if for any reason this is necessary and also for the purpose of permitting the proper setting and adjustment of the tap, especially in those cases where the nuts are comparatively small and where the diameter of the holder will therefore be likewise comparatively small. The spindle carrying this holder is also of tubular form for the passage of the nut-blanks from the tap, and in practice a suitable wire, as 66, may lead down into the spindle the desired distance to receive the nuts from the tap as they are fed upward through the spindle by each successively tapped nut-blank.

The several mechanisms herein described are suitably timed so that on each indexing of the table a nut blank will be brought into position to be tapped and the table locked in such position, whereupon the tap will descend, the tap being continuously rotated during its reciprocatory movements to tap the nut. After the nut has been properly tapped the tap will be, by the cam hereinbefore referred to, raised to permit another indexing of the table, the blanks being fed to the openings provided in the table in the manner hereinbefore described, so that the table openings may be kept full 15 of blanks and each successively and rapidly tapped.

From the foregoing it will be observed that this improved nut tapping machine permits the continuous operation of the tap without any loss of time due to the necessity of removing the tapped blanks from the tap intermediate the tapping operations, and that the tap itself has a continuous rotary movement and an intermittent reciprocatory movement while the blanks are fed thereto by a rotary table, the organization being such that nut-blanks can be rapidly tapped, while the mechanism is very much simplified in comparison with that which 30 has heretofore been necessary for doing the same character of work.

In practice the rotating table is supported within a circular casting 100 carried by the standard and having formed therewith a suitable pan or trough 101, see Fig. 9. The enlarged end of the spindle is bored to the size of the curved tap tube or holder, this being determined by the largest blank the machine is capable of tapping and by 40 the length of the curve of the tube. Beyond the upper end of the tap tube or holder the spindle is bored to accord with the diameter of the largest blank the machine is capable of operating upon. This thus leaves a shoulder at the upper end of the enlarged portion of the spindle against which the tap tube is clamped by means of a clamping collar nut 102.

From the foregoing it will be observed that I have provided an improved upright nut-tapping machine in which various forms of blanks may be readily and quickly tapped by one and the same machine, and in which as each blank is brought into alignment with the tap by means of the indexing mechanism hereinbefore explained the spindle carrying the tap drops by its own weight, thus allowing the tap to engage the blank. The instant the threaded portion of 60 the tap has passed through the blank the plunger 36 is released from the action of the spring plunger 40, whereupon the table may be indexed at the same time that the spindle is raised by the means hereinbefore referred to, carrying the tapped nut-blank

with the tap. This continuous operation causes the nuts to travel off the tap and up the spindle, over the wire, and into a suitable receptacle on the floor, the operations being carried out in practice very rapidly. 70

I claim as my invention:

1. In a nut tapping machine, the combination of a vertically supported tap holder, a crank-formed tap carried thereby, means for automatically lifting the tap holder and permitting it to descend by gravity, and means for rotating said tap holder and thereby the tap through the medium of the tapped nuts. 75

2. In a nut tapping machine, the combination of a vertically supported tap holder, a crank-formed tap carried thereby, means for automatically lifting the tap holder and permitting it to descend by gravity, means for rotating said tap holder and thereby the tap through the medium of the tapped nuts, means located below the tap for feeding blanks thereto, and means located above the tap for receiving the tapped blanks. 80 85

3. In a nut tapping machine, the combination of a vertically supported tap holder, a crank-formed tap carried thereby, means for automatically lifting the tap holder and permitting it to descend by gravity, means for rotating said tap holder and thereby the tap through the medium of the tapped nuts, means located below said tap for feeding blanks thereto, and means for automatically and intermittently shifting the tap holder and blank feeding means in a horizontal rotary path one relatively to the other. 90 95 100

4. In a nut tapping machine, the combination of a vertically supported counterbalanced tap holder, a crank-formed tap carried thereby, cam actuated means for automatically lifting the tap holder and permitting it to descend by gravity, means for rotating said tap holder and thereby the tap through the medium of the tapped blanks, and means for automatically and intermittently shifting the tap holder and blank feeding means in a horizontal rotary path one relatively to the other. 105 110

5. In a nut tapping machine, the combination of a vertically supported tap holder, a crank-formed tap carried thereby, means for reciprocating the tap holder, means for rotating said tap holder and thereby the tap through the medium of the tapped nuts, means located below said tap for feeding blanks thereto, means for automatically and intermittently shifting the tap holder and blank feeding means in a horizontal path one relatively to the other, and means for holding said intermittently rotatable means against movement intermediate its intermittent shifting movements. 115 120 125

6. In a nut tapping machine, the combination of a reciprocatory and rotatable tap holder, means for intermittently reciprocating 130

- ing the tap holder, means for rotating it, and a crank-formed tap carried by said holder and rotated by the holder through the medium of the tapped nuts carried thereby. 5
7. In a nut tapping machine, the combination of a reciprocatory and rotatable tap holder, means for reciprocating the tap holder in a vertical path, means for rotating it during its reciprocatory movements, and a nut tap carried by said holder and having a curved discharge end and rotated by the holder through the medium of the tapped nuts carried by the tap. 10
8. In a nut tapping machine, the combination of a vertically supported reciprocatory and rotatable tap holder, means for intermittently reciprocating the tap holder, means for rotating it, a crank formed tap carried by said holder and rotated by the holder through the medium of the tapped nuts carried thereby, and a horizontal rotary table located under the tap holder and having a series of blank pockets in its upper surface for feeding nut blanks successively to the tap. 15
9. In a nut tapping machine, the combination of a reciprocatory and rotatable hollow spindle, a tap holder carried thereby, a crank formed tap carried by the holder and rotatable by such holder through the medium of the tapped nuts, means for intermittently reciprocating the spindle and its holder, and means for continuously rotating such spindle and holder, the nuts being discharged from the outer end of the spindle. 20
10. In a nut tapping machine, the combination of a reciprocatory and rotatable hollow spindle, a tap holder carried thereby, a crank formed tap carried by the holder and rotatable by such holder through the medium of the tapped nuts, means for intermittently reciprocating the spindle and its holder, means for continuously rotating such spindle and holder, the nuts being discharged from the outer end of the spindle, and means projecting into said spindle for receiving the nuts. 25
11. In a nut tapping machine, the combination of a reciprocatory and rotatable hollow spindle, a tap holder carried thereby, a crank formed tap carried by the holder and rotatable by such holder through the medium of the tapped nuts, means for intermittently reciprocating the spindle and its holder, means for continuously rotating such spindle and holder, the nuts being discharged from the outer end of the spindle, and means projecting into said spindle for receiving the nuts and comprising a wire. 30
12. In a nut tapping machine, the combination of a reciprocatory and rotatable hollow spindle, a tap holder carried thereby, a crank-formed tap carried by the holder and rotatable by such holder through the medium of the tapped nuts, means for intermittently reciprocating the spindle and its holder, means for continuously rotating such spindle and holder, the nuts being discharged from the outer end of the spindle, and means for receiving the nuts and comprising a wire. 35
13. The combination of a horizontally located rotatable table adapted to carry a series of blanks, ratchet mechanism for intermittently rotating said table, a spring controlled reciprocatory bolt for locking it at each indexing of the table, and an automatically operative reciprocatory plunger for successively holding the several blanks against movement in the table and brought into operation on each indexing of the table. 40
14. In a nut tapping machine, the combination of a vertically supported reciprocatory and rotatable tap holder adapted to carry a tap, means for reciprocating the tap holder, means for rotating it, a crank formed tap carried by said holder and rotated thereby through the medium of the tapped nuts, and a hollow spindle carrying said holder and from the outer end of which the nuts pass. 45
15. In a nut tapping machine, the combination of an intermittently reciprocatory and rotatable tubular tap holder, and a tap carried thereby and having its opposite end portions extending in the same general direction but out of the same axial line and having an intermediate deflected portion merging into said end portions, the tap being rotated by the holder through the medium of the tapped blanks. 50
16. The combination of a rotary table for feeding blanks and having a plurality of blank openings, a series of plungers carried by said table and corresponding in number with said openings, and means for successively engaging said plungers to hold the blanks against movement in their openings. 55
17. The combination of means for feeding blanks and having a plurality of blank openings, and a single automatically operative means for all of said openings for successively holding the blanks against movement in their openings and comprising a reciprocatory plunger. 60
18. The combination of means for feeding blanks and having a plurality of blank openings, and a single automatically operative means for all of said openings for successively holding the blanks against movement in their openings and comprising a spring pressed, cam actuated reciprocatory plunger. 65
19. The combination of a rotatable blank table, means for rotating it, said table hav- 70

ing openings for the reception of blanks, plungers located in said table for holding said blanks against movement, and automatically operative means for successively engaging said plungers.

20. The combination of a rotatable blank table, means for rotating it, said table having openings for the reception of blanks, plungers located in said table for holding said blanks against movement, and spring 10 pressed and cam actuated means for automatically and successively engaging said plungers.

21. The combination of a rotatable blank 15 carrier, means for rotating it, said carrier having openings for the reception of the blanks, plungers located in said carrier, one for each blank opening, for holding said blanks against movement, each of said plungers having a serrated end, and means for 20 successively engaging said plungers on the rotation of said carrier to hold the blanks successively in their tapping position.

22. In an automatic nut tapping machine, 25 the combination of a standard, a vertically supported hollow tap holder spindle carried thereby and having a grooved collar, a cam-actuated oscillatory arm having a shoe working in said groove for raising said spindle, 30 and a similarly supported arm carrying a weight and having a shoe also working in said groove.

23. The combination of a horizontally 35 located table having a series of blank receiving openings, cam actuated ratchet mechanism for intermittently rotating said table, the ratchet thereof having a series of teeth corresponding in number with the number of blank openings, means for holding 40 the table in its indexed position, a series of plungers carried by the table one for each blank opening, and a single means for successively engaging all of said plungers.

24. In an automatic nut tapping machine, 45 the combination of a standard, a vertically supported hollow tap holder spindle carried thereby, a tap holder at the lower end thereof adapted to carry a crank-formed tap effective to feed the tapped blanks through 50 the spindle and out therefrom at the upper end thereof, means effective to raise and lower the tap, and means for rotating it.

25. In an automatic nut tapping machine, the combination of a standard, a vertically 55 supported hollow tap holder spindle carried thereby and having a tap holder at its lower end adapted to carry a crank-formed tap effective to discharge tapped blanks through the spindle and out from the upper 60 end thereof, means for automatically raising the tap holder and thereby the tap and permitting it to descend by gravity, and means for rotating the tap holder.

26. In an automatic nut tapping machine, 65 the combination of a standard, a vertically

supported hollow tap holder spindle carried thereby and having a tap holder at its lower end adapted to carry a crank-formed tap effective to discharge tapped blanks through the spindle and out from the upper 70 end thereof, means for raising and lowering the tap holder and thereby the tap a blank carrier, and means for rotating the tap and blank carrier one relatively to the other.

27. In an automatic nut tapping machine, 75 the combination of a standard, a vertically supported hollow tap holder spindle carried thereby and having a tap holder at its lower end adapted to carry a crank-formed tap effective to discharge tapped blanks through 80 the spindle and out from the upper end thereof, means for reciprocating the tap holder and thereby the tap a blank carrier, means for rotating the tap and blank carrier one relatively to the other, and means for 85 carrying the tap and carrier into position to tap successive blanks one relatively to the other.

28. An automatic nut tapping machine comprising a vertically supported reciprocating and rotatable tap holder, a crank-formed tap carried thereby, means for automatically reciprocating and rotating the tap holder, a horizontally located rotatable table supported under the tap for feeding 90 blanks to the tap and having a series of blank carrying pockets in its upper surface whereby a plurality of blanks may be positioned in readiness to be tapped before they reach the tap, means for automatically indexing the table step by step, and means for automatically locking it at each indexing of the table.

29. In a nut tapping machine, the combination of a vertically supported reciprocating and rotatable tap holder, a crank-formed tap carried by such holder and rotated thereby through the medium of the tapped nuts, means for reciprocating the tap holder, means for rotating it, a hollow spindle carrying said holder and from the outer end of which the nuts pass, and means for carrying a series of blanks in a horizontal circular path step by step beneath the tap and constructed to permit the loading of the 100 blanks while the tapping operation is proceeding and so that a plurality of blanks will be positioned in readiness to be tapped prior to reaching the tap.

30. In a nut tapping machine, the combination of a vertically supported intermittently reciprocating and rotatable crank-formed tap, means for reciprocating it, means for rotating it, means for feeding blanks to the lever end of said tap, and means for receiving blanks from the upper end of said tap.

31. In a nut tapping machine, the combination of a vertically supported intermittently reciprocating and rotatable tubular 130

tap holder, a hollow spindle located to support at its lower end the tap holder, a crank-formed tap carried and rotated by said tap holder through the medium of the tapped 5 nuts, means for reciprocating said tap holder and spindle, means for rotating it, means for feeding blanks to the lower end of said tap, and means for receiving said

fed blanks from the upper end of said tap through said spindle.

Signed at Cleveland, Ohio, this 19th day of April, 1911.
